TELEVISION ANTENNA

James Goumas, Perth Amboy, N. J.

Application November 17, 1949, Serial No. 127,921

2 Claims. (Cl. 250—33.65)

1

My invention relates to antenna for radio reception and particularly an antenna system for use indoors with a television set utilizing a wide band of ultra-high frequency oscillations with performance throughout a large number of television channels.

One of the problems hindering the wide use of television is the difficulty experienced in securing satisfactory reception throughout the channels now being devoted to video programs due to lack of sufficient antennization. This problem is often due to the inability of the potential buyer of a television set to procure the permission of his landlord to erect the conventional outdoor type of antenna which is usually mounted on a roof, chimney or like elevated portion of a building. In other cases the buyer of the set may himself object to the appearance of such an antenna or the cost and danger involved in its erection and maintenance. Still other cases may arise where unusually severe conditions of reflected interference are present which interfere with reception throughout certain channels.

It is to be realized that the reception of a video signal to be adequate throughout a single channel must give uniform coverage approximately 500 times the width of the signal of a normal broadcasting band. Therefore, in order to adequately receive over any one of the presently available television channels an antenna must be able to respond and discriminate over a plurality of pronounced unidirectional patterns. If the pattern is not unidirectional the antenna will have a tendency to pick up signals other than those emanating directly from the transmitting station as reflected signals causing multiple images, ghosts, cross lines and like defections to appear in the picture of reproduction. In order to overcome the difficulties of imperfect reproduction it has been considered prior to this time necessary to mount a large antenna system on the roof of the building in which the television set is to be used. These systems are not only expensive in first cost but are also expensive to install and maintain. Furthermore, they do not present a pleasing appearance especially so when a large number are erected on the roof of an apartment house for the tenants living therein. It is therefore one of the objects of the present invention to provide an inexpensive antenna having spaced dipoles and angularly positioned prong-like extensions for unidirectional reception throughout the wide band of a selected video broadcast channel.

2

Another object is to provide an antenna for indoor use that is capable of high gain performance.

Still another object is to provide an antenna having unusual reflecting characteristics.

A further object of the invention is to provide an indoor antenna system for unidirectional reception throughout the full upper and lower limits of the presently used television channels.

A still further object is to provide a dipole antenna having adjusting means indicative of the position of the dipoles relative to specific television channels.

By this invention I obtained improved video reception through the provision of relatively closely spaced folded dipoles to which additional capacitance is added by angularly placed dipole extensions disposed from angularly positioned reflecting rods adapted for installation within a building or like enclosure in close proximity to a television receiving set.

More particularly the invention consists of a novel construction and combination of parts hereinafter described, illustrated in the drawings and pointed out in the appended claims; it being understood that various changes and variations in form, size, and materials may be resorted to without departing from the claims or sacrificing any of the advantages of the invention as illustrated in the drawings wherein like numbers refer to like parts in the various views.

In the drawings:

Figure 1 is a plan view of the antenna system of this invention.

Figure 2 is a side elevational view of the antenna.

Figure 3 is an end view showing the arrangement of the dipoles.

Figure 4 is a detail of the connections to the dipoles.

Figure 5 is a sectional detail of the mount construction.

Figure 6 is a plan view of a modified form of mount provided with adjusting and indicating means.

Figure 7 is a partial section of the base taken on line 7—7 of Figure 6.

Referring now in detail to the drawings, in Figure 2 the antenna assemblage of this invention is shown generally at 10. The antenna is mounted on a suitable base 11 of sufficient weight to support the assemblage in an upright position but light enough to allow the assemblage to be readily moved as desired. The antenna is proportioned so that it can be either set on top of a tele-

vision cabinet or placed on the floor adjacent thereto as found to suit the individual preference of the user. I have found that a wood base makes a very satisfactory mount means, however, in those cases where a large quantity are to be produced a cast metal base as illustrated may be preferable. The base 11 is preferably formed with a flat top portion 12 having an aperture 13 (Figure 5) of sufficient size to receive a mount sleeve 14 having a flange 15 seated against the top portion. Flange 15 is secured to the top portion 12 against rotation by a screw 16 or like securing means adapted for inserted engagement between the top portion and the flange. The flange 15 is formed with a bore 17 into which an upright member 18 such as a pipe or round shaft is inserted. The upright 18 is secured against axial movement within the sleeve by collars 19 placed in encircled engagement therewith above and below the fixed sleeve and secured to the upright by set screws 20 positioned transversely of the upright.

Seated across the top of the upright 18 is a crossbar 21 having a socket 22 spaced from the ends of the crossbar into which the top end 23 of the upright is inserted and fixedly secured thereto by screw means 24. Although the socket 22 is shown as provided with a screw securing means 24 it is to be understood that in those instances where demountability is not desired a weld juncture means between the upright and crossbar either with or without a socket can be used. Crossbar 21 is preferably of flat strip construction to provide a flat top on which is mounted at each end thereof flat mount pads or insulators 24. Pads 24 are substantially rectangular in shape and are formed of any suitable dielectric material of sufficient thickness to stop conduction of currents accumulated either in the reflectors and dipoles as hereinafter described and the crossbar 21. The pads 24 are secured to the ends of the crossbar 21 by a suitable bolt means 25 inserted therethrough and spaced from the edges of the pads to provide planar insulated attaching areas 26.

At one end of the crossbar 21 mounted on an insulator pad 24 are two pairs 27 and 28 of reflector rods or radiators angularly disposed relative to each other and the crossbar 21 as best illustrated in Figure 1. The pairs of rods 27 and 28 are preferably formed of metal tubing having flattened ends 30 and 32 suitable for bolted attachment to the insulating pad on which they are seated. The outer pair 27 is provided with free ends 29 spaced downwardly and outwardly from the crossbar 21 with flattened ends 30 carried by the insulating pad 24. The two secured ends 32 are electrically bonded together by a strap 31 or like connecting means in engagement therewith. The other pair of rods 28 are spaced inwardly of the first mentioned pair of rods 27 with their flattened ends 32 also mounted on the same insulating pad 24 but are reversed in direction so that their extended ends 33 are disposed upwardly of the crossbar 21. The two mounted ends 32 of rods 28 are electrically bonded together by an arched plate 34, or a suitable wire connector, having a mid-section 35 displaced upwardly from the pad bolt 41. The length, spacing and overall configuration of the two pairs of rods 27 and 28 is such as to provide screen means against undesired radiations and also to act as reflecting means to radiate desired radiations toward the dipoles of the antenna mounted at the opposite end of the crossbar 21 as hereinafter described.

Mounted on the other insulating pad 24 positioned at the other end of the crossbar 21 and spaced from the reflector rods 27 and 28 are a pair of folded dipoles 36 and 37. Both of the dipoles 36 and 37 are preferably formed of metal tubing and of conventional looped construction spaced apart to provide for high and low frequency reception. The outer dipole 36 is of lesser overall dimensions to provide for less capacitance adapted for reception of the high frequency channels with the inner dipole 37 being of greater capacitance and adapted for reception of the low frequency channels. Formed as extensions of the inner dipole 37 are a pair of angularly disposed prong-like extension members 40 having one end of each extension connected with the opposite ends 38 of the inner dipole. The extensions 40 are provided with free ends 41 spaced apart and angularly disposed from the crossbar 21.

The outer and inner dipoles 36 and 37 are respectively spaced apart with their opposite ends 38 and 39 spaced apart and secured to the insulating pad 24 by suitable bolt means 43. The respective ends 38 and 39 of the pair of dipoles are bonded together in parallel by separate bars 42 and 43 respectively as best illustrated in Figure 4. A conventional twin lead television transmission line 44 is utilized as the set lead in with wires 45 and 46 of the line connected to bars 42 and 43 respectively and thence connected to the television set (not shown).

Figures 6 and 7 show a modified form of base for the antenna assemblage 18 wherein the base 11 is provided with a transverse adjusting shaft 149 mounted in the side thereof. Shaft 149 is provided with a driving gear means 150 positioned within the base for engagement with a bevel gear 151 carried by the rotatable upright 18 and secured thereto by a set screw 152. Shaft 149 is provided with knurled knob 153 positioned outside of the base 11 providing for ready manual rotation of shaft 149 to rotate the upright 18. Encircling the upright 18 and secured to the base 11 is a round plate 155 having indicia indicative of channel positions beamed toward the situs of the antenna. Mounted on the upright 18 is a pointer 156 secured to the upright for rotation therewith by a set screw 157. The purpose of the pointer is to provide means of calibration of the antenna assemblage wherein the pointer is correlated with the channel indicia 155 in order that the best reception can be attained for each channel by merely rotating the antenna to a predetermined position. It is to be understood of course that calibration of the assemblage can be readily accomplished as found necessary due to any relocation of the antenna to suit any particular set arrangement desired by the user. In this manner peak performance of a television set throughout a large number of channels can be attained by merely turning the knurled knob 153.

I claim:

1. A television antenna system having a portable supporting base, an upright rotatably mounted in the base with an end vertically extended above the base, a horizontal crossbar fixed to said extended end of the upright and formed with opposite ends spaced from said upright, insulator pads carried at each of said ends of the crossbar, a reflector means mounted one on one of said insulator pads carried by the crossbar, said reflector means being comprised of a plurality of radially extending rods with each of said rods

having an end secured to said pad the opposite end of each rod being angularly displaced relative to each other rod and the crossbar, one pair of said rods being positioned above said crossbar with said secured ends thereof bonded together and a second pair of rods having secured ends bonded together with free ends disposed substantially below the said crossbar, an inner folded dipole mounted on the insulator pad carried at the opposite end of the crossbar and spaced from said reflector, said inner dipole having spaced ends secured to said insulator pad and formed with prong-like extensions extending downwardly from each end thereof, said prong-like members having free ends angularly disposed relative to each other and the crossbar, an outer folded dipole spaced from the inner dipole having spaced ends secured to said insulator pad with said spaced ends positioned adjacent the spaced ends of the inner dipole, and transmission line connecting means connected between said adjacent ends of the spaced dipoles connecting said dipoles in parallel.

2. A television antenna system having a portable supporting base, an upright rotatably mounted in the base with an end vertically extended above the base, a horizontal crossbar fixed to said extended end of the upright and formed with opposite ends spaced from said upright, insulator pads carried at each of said ends of the crossbar, a reflector means mounted on one of said insulator pads carried by the crossbar, said reflector means being comprised of a plurality of radially extending rods with each of said rods having an end secured to said pad the opposite end of each rod being angularly displaced relative to each other rod and the crossbar, one pair
